CLAIM

The ornamental design for a compact dual-band WLAN antenna, as shown and described.

DESCRIPTION

FIG. 1 is a top plan view of a first embodiment of a compact dual-band WLAN antenna showing our new design; and, FIG. 2 is a top plan view of a second embodiment thereof. The black areas comprise the entirety of the claimed design. All elements of the claimed design are flat and coplanar. The broken line showing of the border of the circuit board forms no part of the claimed design.
